UNITED STATES PATENT OFFICE.

OTHO C. DURYEA, OF WATERBURY, CONNECTICUT, ASSIGNOR TO O. C. DURYEA CORPORATION, OF WILMINGTON, DELAWARE, A CORPORATION OF DELAWARE.

BRAKE MECHANISM FOR RAILWAY CARS.

Application filed May 5, 1925. Serial No. 28,243.

This invention relates to brake mechanism for railway rolling stock.

It has heretofore been proposed to provide a railway car comprising a body portion 5 mounted for longitudinal movement relative to the running gear, said movement being yieldingly resisted by suitable means, whereby impact shocks or blows such as are due to "buffing", for example, are prevented from 10 damaging the car structure and its lading.

It has also been proposed to provide a railway car with a center of draft member, extending the length of the same, which member is adapted for longitudinal movement 15 relative to the car body and running gear, whereby damage to the car structure and the lading is prevented. Such a structure is disclosed and claimed in my co-pending application Serial No. 26,267, filed April 20 27, 1925.

In car structures of the above types the elements constituting the brake mechanism, if the car is provided with brakes, must have relative longitudinal movement if certain of 25 said elements are fixedly attached to a part or parts of the car structure adapted for movement relative to other parts of the structure. For example, if the car structure is of the longitudinally movable body type, certain 30 elements of the brake mechanism, such as the brake mast, should be mounted for movement with the car body, while certain other elements, such as the brake beams and brake shoes, should be mounted for movement with 35 the running gear. Relative movement would therefore take place between these elements of the brake mechanism whenever relative movement occurs between the car body and the running gear.

Accordingly it is an object of the present 40 invention to provide novel brake mechanism which is so constructed that relative longitudinal movement between certain parts of the car structure to which one or more elements of said brake mechanism are fixedly 45 secured does not interfere with the proper functioning of the brakes at any time.

Another object of the invention is to provide a train air line composed of sections 50 which are provided with novel connecting means whereby relative movement between said sections will not interfere with the operation of the air control portions of the brake mechanism.

A further object of the invention is to pro-

vide novel means whereby relative movement between brake elements fixedly secured to the running gear is not transmitted to the elements of the brake mechanism fixedly secured to another part or parts of the car 60 structure having longitudinal movement relative to said running gear.

Other objects which will appear more fully hereinafter, include the provision of a 65 simple and rugged brake mechanism which is inexpensive to manufacture and which conforms to the standard brake construction employed at the present time.

The invention will be readily understood by reference to the accompanying drawings, 70 which drawings, however, are for the purpose of illustration only and are not to be taken as defining the limits of the invention, reference being had to the appended claims for this purpose.

In the drawings,

Figs. 1 and 1^a are top plan views illustrating a car structure embodying the present invention, certain elements of the brake mechanism being omitted from the left-hand 80 end of Fig. 1 and certain elements of the car structure being omitted from Fig. 1^a in the interest of clearness;

Fig. 2 is an enlarged detail view in transverse section illustrating one manner in 85 which certain elements of the brake mechanism may be secured to the car body;

Fig. 3 is an enlarged detail view illustrating one form of flexible connection that may be employed between sections of the train air 90 line;

Fig. 4 is a detail view illustrating a second type of flexible connection for the air line sections; and

Fig. 5 is a detail view illustrating another 95 flexible connection which may be employed.

Referring to the drawings, wherein like reference characters refer to like parts throughout the several views, the car structure, on which is mounted the brake mechanism constituting the subject matter of the present invention, is of the longitudinally movable body type. It is to be expressly understood that the particular manner in which certain structural elements of the car 100 are mounted for longitudinal movement relative to another element or elements of the same, constitute no part of the present invention.

In the form shown, the car structure cor- 110

responds to that described and claimed in my co-pending application Serial No. 27,040, filed April 30, 1925, and comprises running gear including a center member 10. Preferably this center member is formed of two longitudinally extending U-shaped channel members 11 (Fig. 2), which are mounted with the flanges of the same extending downwardly, and rigidly secured in any suitable way to the opposite ends of the channel members 11, are draft sills 12 which carry draft gears 13 and couplers 14 of the usual or any suitable type. As will be understood by those skilled in the art, the draft sills 12 are mounted in the usual manner on truck bolsters 15, one of which is partially illustrated in Fig. 1^a, the bolster at the opposite end of the car structure being omitted from Fig. 1 for the sake of clearness.

20 Mounted in any suitable manner on the running gear above described and adapted for limited longitudinal movement relative thereto, is a body structure which preferably includes side sills 16, end sills 17, and a plurality of transverse supporting members including bolsters 18 and any suitable number of cross bearers 19. As shown, the bolsters 18 are rigidly secured at their outer ends to the side sills 16 and have sliding engagement with the draft sills 12. Preferably the cross bearers 19 (Fig. 2) are rigidly attached, as by means of rivets, to the side sills 16 and have sliding frictional engagement with the upper channel member 11 in a manner described and claimed in my co-pending application Serial No. 27,041, filed April 30, 1925.

Suitable means are provided for yieldingly resisting relative longitudinal movement between the car body and the running gear. For example, a pair of coil springs 20 may be operatively secured to the center member and to the bolsters 18 for this purpose, as is described and claimed in my co-pending application Serial No. 27,040.

The brake mechanism constituting the subject matter of this invention is mounted partly on the running gear and partly on the car body previously described. The portion of the brake mechanism mounted on the running gear preferably includes brake shoes 21 which are secured in the usual manner to the opposite ends of the brake beams 22. Pivotal secured to each of the brake beam struts or spreaders 23 are brake beam levers 24 and 25. Preferably the outer brake beam lever 25 is pivotally secured to a fulcrum member 26, which member is attached in any desired manner to the truck bolster 15. Pivotally attached to the adjacent ends of the brake beam levers 24, 25 is a link 27 for imparting motion transmitted from one brake lever to the other brake lever. Attached in the usual manner to the other end 25 of the brake beam lever 24, is an air brake

rod 28. It will be understood that the above described elements, which will be referred to collectively as truck brake rigging, are the same at the opposite ends of the car, and that the present invention is not limited to the use of any particular form of truck rigging since a variety of means may be satisfactorily employed for this purpose. The adjacent inner ends of the air brake rods 28 are connected by a flexible member which, 75 in the form shown, is constituted by a chain 29. Two sections 30 of the train air line, one adjacent each end of the car structure, is fixedly secured to the running gear and preferably to the draft sills 12, as by means of 80 U-shaped bolts 31.

The elements of the brake mechanism rigidly mounted on the car body preferably include an air cylinder 32 provided with a triple valve mechanism 33 of the usual type. 85 Said cylinder 32, which may be secured in any desired manner to the cross bearers 19 and said sills 16, is connected by means of pipe 34, with a brake cylinder 35 of the usual type. Preferably the brake cylinder 90 is mounted in a position to extend transversely of the car structure and is secured to the cross bearers, as by means of bolts 36, which extend through suitable strengthening members 37 that may be constituted 95 by angle irons. The brake cylinder 35 is provided with the usual piston (not shown) and a piston rod 38 which carries at its outer end a rotatably mounted pulley or sheave 39, the latter being preferably 100 mounted to rotate about a vertically disposed pin 40 suitably journaled in said piston rod 38. Rotatably mounted on opposite sides of the piston rod 38 in the plane of the pulley 39, are a pair of pulleys 105 41 which are suitably secured to the body structure by means of a casting 42 which may be attached in any suitable manner to the cross bearers 19. The flexible member 29 connecting the adjacent inner ends of the 110 air brake rods 28 has rolling engagement with each of the pulleys 39 and 41. The bight of this flexible member passes around the pulley 39 and the opposite ends of the same extend inwardly and around the 115 pulleys 41 to said rods. The casting or strengthening member 42 is preferably provided with an integrally formed portion 42^a which constitutes a support for a bell crank lever 43 mounted for pivotal movement 120 about a vertical axis. The short arm of said bell crank lever 43 is secured, as by means of a clevice 44 and a flexible member 45, to the piston rod 38. Pivoted attached to the end of the long arm of the bell crank 125 lever 43 is a hand brake rod 46 which extends outwardly toward one end of the car and is provided on its outer end with a flexible portion 46^a that is secured in a suitable manner to the foot of the brake mast indi- 130

cated in section at 47, Fig. 1. In communication with the air cylinder 32 is a section of the train air line composed of a longitudinally extending pipe 48 and a diagonally disposed pipe 49.

In order to provide for relative longitudinal movement between the train air line section 48, 49 which is attached to the car body and the air line sections 30 attached to the running gear, suitable flexible connections are interposed between said sections. As shown more clearly in Figs. 1 and 3, said flexible connections may comprise two sections of air hose 50 which are secured in any suitable manner to the adjacent ends of the air line sections 30 and 48, 49 and are provided with the usual or any other suitable coupling members 51. If desired, only one section of hose 50 need be employed, as is illustrated in Fig. 4, one of the coupling members 51 being directly secured to the train air line section 30, or to the section 48, 49. If it is not desired to employ a hose as a part of the flexible connection between the sections of the train air line, a rigid pipe 52 (Fig. 5) may be provided at its opposite ends with suitable universal joints 53, which joints are connected respectively to the air line pipe 30 and 48, 49. The flexibility of the pipe 48 will compensate for the transverse shortening of this flexible connection, due to relative movement between the movable parts of the car structure. An air release line 54, which leads from a suitable point in the train air line to one end of the car body, is preferably provided for hand air control of the brake mechanism in a manner well understood in the art.

Operation.—A detailed description of the operation of all of the elements of the braking mechanism is unnecessary since said mechanism conforms closely in operation to the brakes now employed in the usual type of railway cars. It is pointed out, however, that relative longitudinal movement of the car body in either direction is not transmitted to the brake rods 28 and consequently does not affect the position of the brake shoes 21 since the flexible member 29 has rolling engagement with the pulleys 39, 41, whereby relative movement of said pulleys, longitudinally of the running gear, in either direction does not vary or change the tension of said flexible member. If air is admitted into the brake cylinder 35 to move the piston rod 38 outwardly from said cylinder, this movement is transmitted through pulley 39 to flexible member 29 and brake rods 28 to set the brakes as illustrated in Figs. 1 and 1^a. The hand brakes are set by rotation of the mast 47, which motion is transmitted by a flexible member 46^a, hand brake rod 46, and bell crank lever 43 to the flexible member 45, whereby motion is imparted to the brake rods 28 to set the brakes. Relative movement of

the car body does not disrupt the sections of the train air line since the flexible connections interposed between said sections permit this relative movement without danger of breakage in the line. 70

It will thus be perceived that there is provided brake mechanism for a railway car of the longitudinally movable body type which is extremely simple in construction, which closely conforms to brake mechanism 75 at present employed and which is adapted to function at all times regardless of relative longitudinal movement between the elements of said mechanism. Various changes may be made in the details of construction without departing from the spirit of the invention as defined in the following claims. 80

What is claimed is:

1. In combination with a railway car comprising running gear including a center member and a body mounted for longitudinal movement relative to said running gear, brake mechanism for said car including truck brake rigging mounted for movement with said running gear, brake rods having 85 operative engagement with said truck rigging, a flexible member connecting said rods, means including a brake cylinder mounted for movement with said body, a piston rod for said cylinder, and means carried by said rod and having rolling engagement with said flexible member. 90

2. In combination with a railway car comprising running gear including a center member and a body mounted for longitudinal movement relative to said running gear, brake mechanism for said car including truck brake rigging mounted for movement with said running gear, train air line sections mounted for movement with said running gear, means mounted for movement with said body and having operative engagement with said truck rigging, said means including a train air line section, and means connecting said air line sections permitting 105 longitudinal movement therebetween. 110

3. In combination with a railway car comprising a center member and a body mounted for longitudinal movement relative to said member, brake mechanism for said car including fluid pressure means, means actuated by said pressure means including brake shoes, a lever mounted for movement with said body, means connecting said lever with said second named means, a brake mast mounted for movement with said body, and means connecting said mast and lever. 115

4. In combination with a railway car comprising a center member and a body mounted for longitudinal movement relative to said member, brake mechanism for said car including fluid pressure means, means actuated by said pressure means including brake shoes, a lever mounted for movement with said body, flexible means connecting said 125 130

- lever with said second named means, a brake mast mounted for movement with said body, and means connecting said mast and lever.

5. In combination with a railway car comprising a center member and a body mounted for longitudinal movement relative to said member, brake mechanism for said car including brake elements fixedly secured to said body and movable therewith, brake means fixedly secured to said center member for movement therewith, and means connecting said first named means and one or more of said elements permitting relative longitudinal movement therebetween.

10. In combination with a railway car comprising a center member and a body mounted for longitudinal movement relative to said member, brake mechanism for said car including brake elements fixedly secured to said body and movable therewith, brake means fixedly secured to said center member for movement therewith, and flexible means connecting said first named means and one or more of said elements permitting relative longitudinal movement therebetween.

15. In combination with a railway car comprising a center member and a body mounted for longitudinal movement relative to said member, brake mechanism for said car including brake elements fixedly secured to said body and movable therewith, brake means fixedly secured to said center member for movement therewith, and flexible means connecting said first named means and one or more of said elements permitting relative longitudinal movement therebetween.

20. In combination with a railway car having a body mounted for relative longitudinal movement on the running gear thereof, brake mechanism including means carried by the running gear, a flexible member connected thereto, and means carried by said body and having operative engagement with said flexible member regardless of the relative movement between said running gear and body.

25. In combination with a railway car including running gear and a body mounted for longitudinal movement relative to said running gear, truck brake rigging including brake beams carried by the running gear and brake rods having operative engagement with said brake beams, a flexible member connecting the adjacent ends of said rods, means including a brake cylinder secured to said body, a piston for said cylinder, and means secured to said piston and having rolling engagement with said flexible member.

30. A railway car including running gear, a body mounted for longitudinal movement relative to said running gear, and brake mechanism therefor, said mechanism including elements carried by said running gear, a flexible member having operative engagement with said elements, and means carried by the body and operatively engaging said flexible member for maintaining said member under a predetermined tension regardless of movement of the body relative to said running gear.

35. In combination with a railway car having running gear and a body mounted for longitudinal movement relative to said running gear, brake mechanism including brake rods carried by the running gear, means connecting said rods, means carried by said body including a member adapted

40. to be actuated by fluid pressure, and means connecting said member with the first named means, said member being adapted for longitudinal movement relative to said first named means.

45. Brake mechanism for a railway car of the longitudinally movable body type comprising means fixedly secured to the running gear of said car, means fixedly secured to the body of said car including a fluid actuated member, and means operatively connecting said member to said first named means whereby said brake mechanism is operable regardless of the relative position of said body.

50. In combination with a railway car comprising running gear including a center member and a body mounted for longitudinal movement relative to said center member, brake mechanism for said car including means fixedly secured to said center member and movable therewith, means mounted for movement with said body, and flexible means connecting said first and second named means.

55. In combination with a railway car comprising a center member and a body mounted for longitudinal movement relative to said member, brake mechanism for said car including means fixedly secured to said center member and movable therewith, means mounted on said body and movable with the latter, and means operatively connecting said first and second named means, whereby the same are permitted operative relative movement.

60. In combination with a railway car comprising a center member and a body mounted for longitudinal movement relative to said member, brake mechanism for said car including means fixedly secured to said center member and movable therewith, means mounted on said body and movable therewith, and flexible means connecting said first and second named means.

65. In combination with a railway car of the longitudinally movable body type, brake mechanism for said car comprising means fixedly secured to the running gear of said car, means fixedly secured to the body of said car, and means connecting said first and second named means, said body having longitudinal movement relative to said last named means.

70. In combination with a railway car comprising a center member and a body mounted for longitudinal movement relative to said member, brake mechanism for said car including means fixedly secured to said center member and movable therewith, means mounted on said body and movable with the latter, and means operatively connecting said first and second named means, whereby the same are permitted operative relative movement.

75. In combination with a railway car comprising running gear and a body mounted for longitudinal movement relative to said running gear, brake mechanism for said car including means fixedly secured to the running gear and movable therewith, and means fixedly secured to said body and operatively connected to said first named means.

80. In combination with a railway car comprising running gear including a center member and a body mounted for longitudinal movement relative to said center member, brake mechanism for said car including means fixedly secured to said center member and movable therewith, means mounted for movement with said body, and flexible means connecting said first and second named means.

85. In combination with a railway car comprising running gear including a center member and a body mounted for longitudinal movement relative to said center member, brake mechanism for said car including means fixedly secured to said center member and movable therewith, means mounted for movement with said body, and flexible means connecting said first and second named means.

90. In combination with a railway car comprising a center member and a body mounted for longitudinal movement relative to said member, brake mechanism for said car including means fixedly secured to said center member and movable therewith, means mounted on said body and movable with the latter, and means operatively connecting said first and second named means, whereby the same are permitted operative relative movement.

95. In combination with a railway car comprising a center member and a body mounted for longitudinal movement relative to said member, brake mechanism for said car including means fixedly secured to said center member and movable therewith, means mounted on said body and movable with the latter, and means operatively connecting said first and second named means, whereby the same are permitted operative relative movement.

100. In combination with a railway car comprising a center member and a body mounted for longitudinal movement relative to said member, brake mechanism for said car including means fixedly secured to said center member and movable therewith, means mounted on said body and movable with the latter, and means operatively connecting said first and second named means, whereby the same are permitted operative relative movement.

105. In combination with a railway car comprising a center member and a body mounted for longitudinal movement relative to said member, brake mechanism for said car including means fixedly secured to said center member and movable therewith, means mounted on said body and movable with the latter, and means operatively connecting said first and second named means, whereby the same are permitted operative relative movement.

110. In combination with a railway car comprising a center member and a body mounted for longitudinal movement relative to said member, brake mechanism for said car including means fixedly secured to said center member and movable therewith, means mounted on said body and movable with the latter, and means operatively connecting said first and second named means, whereby the same are permitted operative relative movement.

115. In combination with a railway car comprising a center member and a body mounted for longitudinal movement relative to said member, brake mechanism for said car including means fixedly secured to said center member and movable therewith, means mounted on said body and movable with the latter, and means operatively connecting said first and second named means, whereby the same are permitted operative relative movement.

120. In combination with a railway car of the longitudinally movable body type, brake mechanism for said car comprising means fixedly secured to the running gear of said car, means fixedly secured to the body of said car, and means connecting said first and second named means, said body having longitudinal movement relative to said last named means.

125. In combination with a railway car of the longitudinally movable body type, brake mechanism for said car comprising means fixedly secured to the running gear of said car, means fixedly secured to the body of said car, and means connecting said first and second named means, said body having longitudinal movement relative to said last named means.

130. In combination with a railway car of the longitudinally movable body type, brake mechanism for said car comprising means fixedly secured to the running gear of said car, means fixedly secured to the body of said car, and means connecting said first and second named means, said body having longitudinal movement relative to said last named means.

mechanism for said car comprising means fixedly secured to the running gear of said car, means fixedly secured to the body of said car, and flexible means connecting said first and second named means, said body having limited longitudinal movement relative to said flexible means.

18. In combination with a railway car of the longitudinally movable body type, brake mechanism for said car comprising means including brake rods fixedly secured to the running gear of said car, a flexible member connecting said rods, and means secured to the body of said car and movable therewith, said last named means including a plurality of pulleys having rolling engagement with said flexible member.

19. In a car structure, a car body, a center member extending substantially the length of the body and mounted for movement relative to said body, yielding means for resisting movement of the center member relative to said body, couplers movably connected to the opposite ends of the center member, 25 brake mechanism including a train air line section connected to said body and a train

air line section connected to the center member adjacent the end thereof, and flexible means connecting said sections whereby the sections have operative engagement regardless of the relative movement of the center member and body. 30

20. In a car structure, a car body, a center member mounted for longitudinal movement relative to said body, yielding means for resisting movement of the member relative to the body whereby draft and buffing forces are absorbed, a coupler operatively connected to said center member, brake mechanism for the structure including a train 40 air line section connected to and movable with the body, a train air line section connected to the outer end of said member and movable therewith, the second named section being adapted for connection with the air 45 line of an adjacent coupled car, and a yielding air line section connecting said first and second named sections.

In testimony whereof I have signed this specification.

OTHO C. DURYEA.
